UNITED STATES PATENT OFFICE.

WILLIAM MILLS, OF BIRMINGHAM, AND WILLIAM MORGAN, OF BRISTOL, ENGLAND.

HAND-GRENADE, INCENDIARY AND OTHER BOMB, AND THE LIKE.

1,213,397.

Specification of Letters Patent. Patented Jan. 23, 1917.

Application filed May 8, 1916. Serial No. 96,138.

To all whom it may concern:

Be it known that we, WILLIAM MILLS, a subject of the Kingdom of Great Britain, residing at Bridge street west, Birmingham, 5 in the county of Warwick, England, engineer, and WILLIAM MORGAN, a subject of the Kingdom of Great Britain, residing at 45 Westbury road, Bristol, in the county of Gloucester, England, professor of engineering, have invented certain new and useful Improvements in or Relating to Hand-Grenades, Incendiary and other Bombs, and the like, of which the following is a specification.

15 This invention relates to hand grenades and the like, of the type in which the member for firing the grenade is adapted to be controlled by a member adapted to be held by the hand grasping the grenade.

20 According to the present invention, the arrangement is such that the action of grasping the grenade by the hand is adapted to disengage the controlling member from the firing member to permit of the operation of the 25 latter.

Conveniently the grenade is adapted to be fired by a part adapted to be operated by being pressed inwardly into or toward the body of the grenade, as for instance by grasping 30 the grenade and concussively striking a hard resistance part or member, such as the butt of a rifle, or other part or object with the external part adapted to fire the time fuse, by which operation such part is suitably displaced or operated. In such a grenade the 35 firing member is normally locked or retained from operation by the member adapted to be gripped by the act of grasping the grenade; such member is of a character that when in 40 its normal or locking condition it occupies a position in relief from the grenade so that upon the grenade being grasped, the part of the locking member normally occupying a 45 position in relief in relation to the grenade is necessarily and automatically displaced in such a manner that the locking member is disengaged from the firing member. If it should not be desired after the grenade has been grasped, to fire the grenade and throw 50 it, in releasing the grasp upon the grenade, the locking member again automatically comes into engagement with the firing member and thereby restrains the latter from accidental displacement. Thus except when

the grenade is grasped by the hand, the locking member automatically assumes its condition of engagement with the firing member so that if this should be prematurely subjected to concussion as for instance by the accidental dropping of the grenade, or by reason of the grenade being subjected to shock in transit, the grenade is not fired.

The invention is applicable, in addition to hand grenades, to incendiary and other bombs and the like.

In order that this invention may be clearly understood and readily carried into practice, reference may be had to the appended explanatory sheet of drawings, upon which:—

Figure 1 is a front elevation of one form 70 of grenade according to the present invention. Fig. 2 is a sectional side elevation of the grenade shown in Fig. 1. Fig. 3 is a plan of the grenade shown in Figs. 1 and 2. Fig. 4 is a sectional plan of the grenade 75 shown in Figs. 1, 2 and 3. Figs. 5, 6 and 7 are respectively a front elevation, plan, and side elevation of the locking or retaining means.

In a convenient embodiment of the present 80 invention, we may employ a grenade comprising or involving an oval hollow body or shell *a*, through the one end of which a longitudinally or axially moving striker *b* is incorporated to project. This hollow body or 85 shell may be open at one end only, and such open extremity may be formed with a neck and may be internally screw-threaded.

c is a plug adapted to be screwed into the neck of the shell or body, and said plug *c* 90 carries a casing *d* which may be sweated within the plug *c* and which is adapted to contain the detonator *e* adapted to fire the charge contained within the shell *a*, and with which detonator *e* a length of Bickford time fuse *f* is in communication, such fuse *f* being adapted to be fired by a percussion cap *g*, upon which the striker *b* is adapted to operate. The striker *b* is mounted in a second plug *h* which is adapted to be screwed into 100 the neck of the shell or body, and the inner end of such plug *h* may bear upon an eyelet *i* of angle section which is forced or secured within or in relation to the casing *d*, and within which eyelet the percussion cap *g* is 105 forced.

The striker is normally retained in the position shown in Fig. 2 by a pin, wire or

the like *j* passing through the plug *h* and through the striker and which pin or the like *j* is adapted to be sheared when the outer extremity of the striker is axially impelled inwardly. The striker may be furnished at its outer extremity with an enlarged flat or other shaped head *k* for which purpose it may for instance be operated by the thrower concussively striking any suitable resistance with the enlarged head *k* of the striker. Advantageously the head *k* is adapted to rotate in relation to the striker so that the screwing up of the plug *h* cannot be affected by the head *k*, this precaution having for its purpose to avoid the possibility of the pin or the like *j* being sheared as it might be if the member *k* were fixed and an attempt were made to screw up the plug *h* by the member *k*.

In addition to the member *j*, the striker is normally retained in the position shown in Fig. 2 by the safety member *l*. This in the arrangement shown comprises a U-shaped wire member, the arms of which may extend throughout the major part of the axial length of the grenade, and which are at their extremities bent outwardly in the form of trunnions *m* adapted to engage within perforations in lugs *n* provided integrally upon the shell *a* of the grenade. At a point level with the top of the grenade, the arms of the member *l* turn inwardly of the grenade and extend in a horizontal plane, conveniently contiguous to the upper surface of the plug *h*, to a point at which the transverse part of the U embraces a grooved part *o* of the striker *b*. Beyond the transverse portion *p*, which may be of semi-circular form to satisfactorily engage with the grooved part *o*, the arms of the safety member continue at a greater distance from each other in parallel formation. A part or parts of the safety member at the side of the grenade are disposed at a position projecting in relief from the body of the grenade. In this position the safety member is normally retained by lugs *q* provided on the grenade body, and which lugs *q* are in contact with the lower portions of the safety member. When the safety member occupies this normal position shown in Fig. 2, the part *p* is in engagement with the grooved part *o* of the striker in such a manner as to lock or retain the latter from inward movement. When the grenade, together with the safety member *l*, is grasped by the hand, the safety member is, by reason of its being of a springy character, pressed by the hand toward the body of the grenade, and this has the effect of displacing the part *p* from out of the groove in the striker, and of bringing the wider portion of the inturned part of the safety member into a position embracing the striker so that the grooved part of the latter is not then engaged by

the safety member. The latter can then be concussively operated to shear the pin or the like *j* and explode the percussion cap *g*.

The member *l* normally assumes the position shown in Fig. 2 by reason of the engagement of its trunnions with the perforations in the lugs *n*, and by reason of the lugs *q*, and when the body of the grenade is grasped by the hand, the safety member is adapted to bend by a spring action above the members *q* in a direction toward the body of the grenade, to thereby effect the desired release. Lugs may be provided upon the upper part of the body of the grenade to project and occupy positions one on each side of the projecting corner portion or portions *r* of the safety member; these lugs are adapted to counteract the possibility of the member *l* being operated to release the striker in the event of the grenade being accidentally dropped in such a way that the member *k* might be depressed almost at the same time. The lug or lugs last referred to may also project between the limbs of the member *l* and may be adapted to prevent lateral derangement of the member *l* or of either or both of the limbs thereof, when the latter is depressed by the hand grasping the grenade.

In any of the arrangements above described, if after the safety member has been pressed out of engagement with the striker, it should not be opportune to operate the latter, upon releasing the grasp upon the grenade the safety member automatically moves to again engage with the striker, and thereby lock or retain the latter from accidental operation.

The pivotal connection between the lever and the grenade body is advantageously of a character whereby the lever may be entirely disconnected and readily assembled. This permits of the firing unit being transported separately from the body of the grenade and charge contained therein, so that it can be readily assembled within the latter after it has been transported. The safety members *l* may furthermore be disconnected from a number of the grenades if it should be desirable to do so immediately prior to an engagement.

Suitable provision is incorporated for venting in the vicinity of the explosive part of the cap and/or for venting the space between the explosive part of the cap and the time fuse.

What we claim as our invention, and desire to secure by Letters Patent is:—

1. In a hand grenade, incendiary or other bomb, or the like, the combination with a hollow body of means whereby a charge in the said body may be fired, and means whereby said firing means may be controlled, said controlling means being adapted to be gripped or held by the hand grasping said

body, and said controlling means being so arranged with relation to the said body that the action of grasping the said body by the hand is adapted to disengage the controlling means from the firing means.

5 2. In a hand grenade, incendiary or other bomb, or the like, the combination with a hollow body of means whereby a charge in the said body may be fired, and means whereby said firing means may be controlled, said controlling means being adapted to be gripped or held by the hand grasping said body, and said controlling means being so arranged with relation to the said body that the action of grasping the said body by the hand is adapted to disengage the controlling means from the firing means, said controlling means being separable from the grenade when desired.

10 3. A grenade, comprising in combination a hollow body, a firing member carried by said body mounted to move axially thereof,

one extremity of said member being disposed externally of the body, and said extremity being adapted to be concussively operated inwardly, a resistance member normally retaining said striker in position, said resistance member being adapted to be overcome when the striker is concussively operated, and additional means for normally maintaining said striker in an inoperative condition comprising a safety member, said safety member being normally disposed in relief in relation to the body of the grenade whereby it may be automatically displaced by the action of the hand in grasping the latter.

15 In witness whereof we have hereunto set our hands in the presence of two witnesses.
